NITRURES, OF PARIS, FRANCE.

PROCESS FOR CARRYING OUT CHEMICAL REACTIONS.

1,217,842.

Specification of Letters Patent. Patented Feb. 27, 1917.

Application filed January 26, 1914. Serial No. 814,549.

To all whom it may concern:

Be it known that I, OTTOKAR SERPEK, a subject of the Emperor of Austria-Hungary, and a resident of Paris, France, (whose post office address is 12 Rue Roqueline, Paris,) have invented a new and useful Process for Carrying Out Chemical Reactions, of which the following is a specification.

The present application for patent relates to a special form of carrying out chemical reactions between solid bodies and gaseous bodies, in which the bodies which are to react pass with a speed approaching that of free fall in relatively constricted spaces heated to the desired temperature. It consists in the fact that the gaseous current does not pass through the zone of reaction along the same path as the solid substances, but penetrates thereinto or passes out therefrom through the walls which are intentionally made sufficiently permeable to the gases.

By way of example, there is shown upon the annexed drawing in vertical section (Figure 1) and in cross section (Fig. 2) an apparatus allowing the application of the principle. In the description which follows, it will be supposed that this furnace is utilized for the manufacture of aluminium nitrid in accordance with the process described in my copending application Ser. No. 796913.

The apparatus consists essentially of a pile or stack of carbon washers *a* resting at bottom upon an electrode *A* and supporting at top an electrode *A'*. This stack of washers is surrounded by a sheet metal cover *B*, perfectly gas-tight and lined internally with highly refractory material *C*, for example aluminium nitrid. In order to support the stack of washers in spite of distortions due to the high temperature to which they are to be raised, the space between the stack and the refractory lining *C* is filled with permeable refractory material *E*, for example petroleum coke.

The solid substances (mixture of alumina and carbon) contained in a hopper *G*, which can be opened or closed by means of a dis-tributor *g*, fall into the tube formed by the washers which are heated electrically by resistance. The nitrogen conveyed by the pipe *D* enters at *d'* into the central tube and leaves the latter through the spaces nat-

urally existing between the washers, finally 55 escaping from the apparatus through the pipes *e'* and *e''*.

Instead of entering at *d'*, the nitrogen might enter at *d²* or again at *d³*, *d⁴* according to the position given to the cocks *f'* 60 *f²*, *f³*, *f⁴*. When the nitrogen enters at *d³* or *d⁴*, it passes transversely through the whole apparatus, and in particular it penetrates within the washers before escaping at *e'* *e''*. 65 In this case there may be arranged a vertical partition *E'* (Fig. 2) which compels the gases to pass through the tube in order to go from *d³* *d⁴* to *e'* *e''*.

To simplify the construction, the stack of washers might be dispensed with and the heating effected by the resistance of the filling material *E*, care being taken of course to provide therein a passage sufficient to allow the fall of the solid substances. 70

Again the stack of washers might be replaced by a tube having a large number of perforations in its height.

The gases leaving the apparatus may pass into a second similar apparatus, then into a third, and so on, so long as these 80 gases do not contain large quantities of carbon monoxid. At this moment, the gases may be allowed to escape, or the carbon monoxid separated, or the gas may be mixed with pure nitrogen so as to restore a sufficient content of nitrogen. 85

Instead of being heated by resistance as in the above example, the cavity in which the reaction takes place might be heated by means of electric flames, the walls of this 90 cavity being porous so as to allow the passage of the gases.

The method of procedure which forms the subject of this invention presents the advantage of being readily able to bring a 95 larger quantity of gas into contact with the solid materials. Indeed, if in the apparatus described, the gas enters at one end and leaves at the other, and if it be desired to pass a large quantity of gas, the speed of 100 the latter will necessarily be very great. On the contrary, with the arrangement of the present invention, if the speed of the gas is still great when it enters at one end of the tube, it diminishes continually and 105 quickly enough to become *nil* at the other end. When the two passages take place through the wall, the speed is low at all

points. In this way the speed is never sufficiently violent to affect the passage of the solid materials.

Example: Let it be supposed that in order to treat a certain quantity of materials, it is necessary to pass two cubic meters of gas per minute through a tube of 10 centimeters diameter and five meters high. If the gas were to enter at one end of the tube and leave at the other, its speed would be about 4 meters per second. If on the contrary this gas passes through the tube in the transverse direction, entering on one side of the wall and leaving at the other, its speed will be only 4 meters per minute.

The process of obtaining aluminium nitrid herein intended to be claimed is specific in respect to the manner of flow of the gas. My invention in its broader aspects forms 20 the subject of my Patent No. 1,212,119, dated January 9, 1917.

I claim as my invention:—

1. A process of obtaining aluminium nitrid, by projecting aluminous material and carbon in powdered form through nitrogen in an inclosed space through the walls of which the nitrogen is caused to flow and heated to the temperature of the reaction. 25

2. A process of obtaining aluminium nitrid by projecting aluminous material and carbon in powdered form through a space through which nitrogen is caused to flow in a direction across the flow of powdered material and heated to the temperature of the reaction. 30

In testimony whereof I have signed my name to this specification, in the presence of two subscribing witnesses.

OTTOKAR SERPEK.
